13 Claims. (Cl. 340—324)

This invention relates to the field of display devices. More particularly it relates to a novel display panel which, though compact in size and low in cost, is capable of displaying a large number of unique conditions.

One common use of display systems is in connection with contemporary data processing equipment such as computers, processors, tabulators and the like. This invention will be described in connection with such a unit though it should be understood its use is not so limited but, instead, can be used wherever it is a requirement that a large number of points in a unit be monitorable in a relatively small space as, for example, to indicate to maintenance personnel or to the operator the area wherein a difficulty exists causing the unit to malfunction.

In the past, if sufficient information was to be provided this had necessitated an extensive console type arrangement perhaps a separate unit being provided with a display panel having an indicator for each one of the control points which is monitored. When the control point has a normal signal level thereat the lamp at the console display panel is in a first condition, e.g. Off, and when that control point is malfunctioning then the corresponding lamp on the control panel would be placed in its other position, e.g. On, indicating to the operator that a difficulty exists. During the following discussion it should be realized that alternative arrangements are equally possible. For example, the indicators at the panel could be normally On, being turned off by detection of a chosen signal at a monitored point.

While this approach has been necessary and may be desirable with large scale data processing systems, it is awkward and impractical for the smaller units which do not normally have the physical size to permit a full console display panel and further whose cost does not allow the inclusion of such a panel either on the unit itself or as a separate, auxiliary unit.

Accordingly, it is an object of this invention to provide a novel display unit.

It is a further object of this invention to provide a display unit for a data processing machine.

It is a still further object of this invention to provide a display unit for a data processing machine which, though compact in size, can provide access to a large number of control points within the unit.

Other and further objects and advantages of the invention will be clear when the following description is read in conjunction with the accompanying drawings.

Briefly stated, the invention provides a display unit for monitoring a plurality of points. The display unit includes a number of indicators and means bearing a number of indicia for each indicator. The indicia bearing means is selectively positionable. Each indicium refers to a different point to be monitored. The apparatus used to position the indicia also establishes a set of connections, through a gating circuit, from each selected indicator to the point corresponding to the indicium positioned at that indicator.

Referring now to the figures:

FIG. 1 is a logic diagram of an exemplary gate circuit used in the invention.

FIG. 2 is a representation of the switch means used to condition the gate circuit of FIG. 1.

2

FIG. 3 is a schematic diagram of a portion of the gate circuit shown in logic form in FIG. 1.

FIG. 4 is a representation of a display panel in accordance with one embodiment of this invention.

FIG. 5 is a perspective view of a portion of the mechanism associated with the display panel of FIG. 4.

FIG. 6 is a perspective view of another embodiment of the mechanism shown in FIG. 5.

FIG. 7 is a view of a display panel used in conjunction with the mechanism shown in FIG. 6.

Referring now to FIG. 1 a gate circuit having four output lines labeled Neon 1—Neon 4 is shown. It will be understood that in a preferred embodiment of the invention eight such circuits would be provided providing output signals for 32 Neon indicators. Since these circuits are identical it is believed unnecessary to include more than the one exemplary embodiment. Each of the output lines will be effective when they receive a high signal from associated inverter amplifiers 10, 11, 12 and 13. Associated with each of these amplifiers is a low Or gate 14, 15, 16 and 17, respectively, and each of these low Or gates buffs nine inputs from nine low And gates making a total of 36 low And gates in all, identified by reference numerals 18—53. The low "Or" gates 14, 15, 16, and 17 will produce a low output if any input is low and will produce a high output if all inputs are high. The low "And" gates, such as gate 27, will produce a low output if all inputs (two in this instance) are low and a high input if any input is high. The inverter amplifiers 10, 11, 12 and 13 produce high outputs if the inputs are low and produce low outputs if the inputs are high.

One input to each of these And gates is provided by the switch associated with the indicia selection mechanism shown in FIG. 2. In the preferred embodiment there are nine switch positions and only one of the vertical lines in FIG. 1 will be low for selected mask. These lines are labeled A—I. The other input to each of these And gates is provided from desired test points throughout the unit with which the display system is associated, e.g. Processor, Computer, Tabulator, Punch, etc. One of the 36 inputs associated with the portion of the circuit illustrated might, for example, be connected to the carry flipflop of an arithmetic unit of a computer or processor, another to a switch associated with card feeding on a punch card reader or punch, etc. The 36 input terminals are labeled 54—89, respectively. Input terminals 54—62 are associated with And gates 18—26, respectively, and the output of these And gates control the lighting of Neon 1 through Or gate 14 and inverter amplifier 10. Inputs 63—71 are similarly associated with Neon 2, inputs 72—80 are associated with Neon 3 and inputs 81—89 are associated with Neon 4.

The operation of this circuit is not believed to require extensive explanation. For example, if the indicia position is selected that will provide a low signal on line A, then each of And gates 26, 35, 44 and 53 will have a first low input applied thereat. Thereafter, if a low signal appears at any one or more of the terminals 62, 71, 80, or 89, the respective "And" gates 26, 35, 44 or 53 will have a low signal on both its inputs causing the respective "And" gate to produce a low output. "And" gates receiving high signals will produce highs at their outputs. The outputs of the "And" gates 26, 35, 44 and 53 are fed to their respective "Or" gates 14, 15, 16 and 17. Those "Or" gates receiving low inputs produce low outputs which are inverted by the respective inverter amplifiers 10, 11, 12 and 13 to produce a high output signal causing the associated neon lamp 1, 2, 3 or 4 to be lit, indicating the presence of the tested for signal. Those "Or" gates receiving high inputs produce high outputs which are inverted to low output signals by the inverter amplifiers. The low signal outputs fail to light the associated Neon lamps thus indicating the absence of the signal.

tested for. Similar tracings of the circuits associated with indicia positions identified by lines B-I yield the same results. Each of the nine input lines enables one of the nine And gates associated with each of the four Neons. The Neon is then under the control of the input line of the selected gate.

Referring now to FIG. 2 a switch arrangement is shown for providing the signals which appear on one of lines A-I of FIG. 1. The output lines of FIG. 2 are similarly labeled A-I corresponding to the lines in FIG. 1. It is evident from this figure that as Arm 90 of switch 91 is rotated, a negative potential of approximately -30 volts will be applied sequentially to the lines labeled E, H, I, D, C, G, B, F, and A in that order. At the same time rotatating member 92 will ground those 8 of the 9 wires which do not have the -30 volts applied thereto. As will be seen from the discussion of FIGS. 5 and 6, Arm 90 and element 92 are controlled by a wheel or dial which in turn may be manually operated to change the indicia on the display panel itself.

FIG. 3 is a schematic diagram of a portion of the circuit shown in logic form in FIG. 1. This circuit includes a switch or drive element for controlling each of the Neons used on the display panel. In the preferred embodiment there are 32 such Neons and accordingly 32 drive elements. Again in the preferred embodiment and as illustrated in the schematic this drive element is a transistor, and two are shown labeled Q1 and Q2 respectively.

The output to drive the Neons is taken from the collector of each transistor and these transistors are operated in the grounded emitter base input mode. While PNP type transistors are shown, if desired NPN transistors could be employed with suitable alteration in biasing and signal levels. If we consider transistor Q1 and the lines feeding the base thereof as the equivalent of amplifier 10 and OR gate 14 of FIG. 1 and transistor Q2 the equivalent of amplifier 11 and Or gate 15 of FIG. 1, then transistor Q1 will control Neon 1 and transistor Q2 will control Neon 2 as indicated at the outputs of the two transistors. The input terminals at the left of this figure are labeled to correspond to the terminals shown in FIG. 1. It is obvious, for example, that if a signal is low at terminal 54 it will have no effect on transistor Q1 which is normally biased or in the Off or non-conducting condition unless the signal on the line labeled E is coincidentally low. Only in this case will the effect of diodes 93 and 94 be such as to permit the base of transistor Q1 to be made more negative driving that transistor into conduction and providing a more positive signal at the collector thereof.

Referring now to FIG. 4, one embodiment of a display panel in accordance with this invention is shown. This panel mounted on a piece of equipment which is to be monitored comprises a masking portion 95 having four longitudinal apertures, 96, 97, 98 and 99. In the embodiment shown since there are 32 indicators or Neons provided, each aperture contains 8 subdivisions or windows, each window having an indicator or Neon associated therewith. By means of control gearing shown in subsequent figures a translucent sheet or membrane mounted behind panel 95 can be moved upwards or downwards so that different portions of the sheet can be positioned to appear at the four apertures.

A translucent sheet capable of operating with the display panel of FIG. 4 and with the switch arrangement of FIG. 2 would have nine distinct positions, so that nine different indicia groupings would be visible in the windows, such as window 100. In any position some or all of the areas visible through apertures 96-99 would have labels thereon indicating the unit point to which the indicator lamp associated with that particular window is connected. Thus, if aperture 96 had window 100 associated with a flipflop involved in a card reader malfunc-

tion this window might show the indicium "READ" as indicated, and might be lit only when there was an error in the card reader section of the unit with which the display panel is associated.

Since each position of the translucent sheet is capable of displaying 32 points of the unit being monitored and since there are 9 sheet positions, a total of 288 display points are possible. It is, of course, easy to see how this could be expanded, still maintaining substantial space savings, in very simple fashion either by providing more than 9 translucent sheet positions or by increasing the number of window positions per slot with a consequent increase in indicators or Neons. It is further clear that while panel 95 is shown, having horizontal apertures these could easily be vertical instead, with the sheet movable from right to left.

FIG. 5 shows a back view of the portion of the machine having the display panel shown in FIG. 4. As is seen a pair of supports are provided, indicated at 101, to mount the display panel and associated components on the unit to be monitored. The display panel bears reference numeral 95 as it did in FIG. 4. Attached to supports 101 are four arrays of indicators or Neons shown by reference numerals 102, 103, 104 and 105. Each indicator or Neon in each of these 4 arrays would be located behind one window portion of panel 95 as was described in connection with discussion of FIG. 4. The translucent sheet referred to but not shown in FIG. 4 is denominated by reference numeral 106. As is seen this translucent sheet, such as glass or plastic, is connected to a rack mechanism 107 which is operated by a pinion and associated gear train indicated at 108. Gear train 108 in turn is driven by a wheel 109 which, in the embodiment shown, is to be manually operated.

On the same shaft as wheel 109 is the switch mechanism shown in FIG. 2. As wheel 109 is rotated, rack 107 will carry translucent sheet 106 upwards or downwards behind mask 95 through the action of pinion and gear train 108. As translucent sheet 106 reaches each of its 9 positions, switch 91 will reach an associated one of its 9 positions making the appropriate circuit connections through the switch circuit shown in FIG. 2. At any given position one of the nine lines of switch 91 is applied to the gating circuit shown in FIG. 1 at which time appropriate signals from the unit points being monitored will cause a given indicator or Neon to be lit showing through the translucent sheet 106 and illuminating the indicium at that window to the operator or maintenance personnel.

Referring now to FIG. 6, a further embodiment of the operating mechanism associated with the circuitry shown in FIGS. 1-3 is presented. The indicator or Neon lamp arrays cannot be seen in this figure but terminal strips for the lamp are indicated by reference numerals 110, 111, 112, and 113. In place of the translucent plate 106 of FIG. 5 four drums are provided, denoted by reference numerals 114, 115, 116 and 117 respectively. These drums have a nonagonal cross-sectional area and each of the 9 plates carry 8 areas each, each of the areas corresponding to one of the windows of the display panel itself and some or as many as all of these areas are appropriately labeled to indicate a point in the unit to be monitored that is associated with the indicator or Neon at that particular window. The thumb wheel of FIG. 5 is also employed in FIG. 6, identified by the same reference numeral 109 but instead of the rack and pinion arrangement of FIG. 5 a gear is provided operated directly from the thumb wheel, and connected to each of the four drums. These gears are indicated broadly by reference numeral 118. The switch of FIG. 2 is also employed in this embodiment and is indicated by the same reference numeral again, i.e. numeral 91.

The advantages of this type of construction can be more clearly appreciated by reference to FIG. 7 which

shows a front view of a display panel which might be utilized with the mechanism shown in FIG. 6. With this type of display panel the Neon array remains uncovered and only the indicium beneath each Neon or indicator is changed by rotation of the drums. This permits a larger area both for the labeling of the window as well as for the visible light of the indicator.

While what has been shown and described is believed to be the preferred embodiments of and the best modes of practicing this invention, it will be clear to those skilled in the art that modifications and variations may be made therein without departing from the spirit or scope of the invention. Accordingly, it is intended to limit the scope of the invention solely by appended claims.

What is claimed is:

1. A display unit for indicating the potential at a plurality of points including a number of indicators, a mask having a number of apertures equal to said number of indicators, control means for selectively positioning said apertures relative to said indicators, a gate circuit for connecting a different one of a first portion of said plurality of points to each of said indicators, and a switching circuit adapted to be controlled by said control means to connect a different one of a second portion of said plurality of points to each of said indicators.

2. A display unit for monitoring a number of points including at least one group of indicators capable of being actuated, a gate circuit connecting each of said indicators to at least two different ones of said points, each of said points capable of exhibiting first or second potentials thereat, said first potential being effective to cause the actuation of said indicators, a multiposition switch for applying a gating signal to permit the enabling of a different one of said points associated with each different indicator for each position of said switch, indicia carrying means associated with said indicators, said indicia carrying means having an indicium for each point connected to each indicator, means for positioning said indicia carrying means so that a desired indicium is closest to its associated indicator, said means for positioning said indicia carrying means also positioning said multiposition switch, whereby the indicium closest to each indicator identifies the point connected to said indicator which is enabled.

3. A display unit including a substantially rectangular mask having a plurality of apertures substantially parallel to a pair of opposite sides of said rectangle, a plurality of indicator lamps positioned behind each of said apertures and visible thereto, a light permeable sheet adapted to be placed at a plurality of positions located between said indicator lamps and said mask, indicia formed on said sheet and associated with each of said indicator lamps, positioning means for selecting one of said plurality of positions for said sheet, each of said sheet positions exposing through said mask apertures one indicium for each of said indicator lamps, a plurality of points capable of exhibiting first or second potentials, gate circuitry connecting each of said indicator lamps to different ones of said points, said indicator lamps operable in response to the detection of said first potential, said gate circuitry including enabling means for permitting the potential at only one of said plurality of points associated with each indicator lamp to be applied to its said associated lamp, said enabling means being controlled by said positioning means whereby the indicium visible for each indicator lamp in any sheet position identifies the point connected to said indicator lamp made effective by said enabling means.

4. The unit defined in claim 3 wherein said positioning means includes a rack affixed to said sheet and a pinion manually rotatable.

5. The unit defined in claim 3 wherein said gate circuitry includes an And gate associated with each of said points, the output of said And gate being connected

to the indicator lamp associated with said point, one input of each of said And gates connected to its said associate point and a second input connected to said enabling means.

5 6. The unit defined in claim 3 wherein said gate circuitry includes an And gate having two inputs and an output associated with each of said points, an Or gate having a plurality of inputs and an output associated with each of said indicator lamps, the output of each of said 10 Or gates being connected to a different one of said indicator lamps, the output of each of a number of said And gates, said number being no greater than the number of said sheet positions, connected to the inputs of said Or gates, one input of each of said And gates connected to its associated point, the other input of each of said And gates connected to said enabling means, said enabling means being chosen so that a different one of said And gates associated with each of said Or gates receives an enabling input for each different sheet position.

20 7. The unit defined in claim 6 wherein said enabling means includes a multiposition switch having a different position determined by each different sheet position.

8. A display unit for monitoring a number of points 25 including a panel having a first plurality of translucent portions, a number of indicator lamps adapted to be actuated positioned behind each of said portions, a rotatably mounted drum associated with each of said portions and located behind said panel, each of said drums 30 having a plurality of rows of indicia on its surface, one column of said indicia associated with each different indicator lamp, means for rotating said drums to display desired rows of said indicia at said portions, gate means selectively connecting a chosen one of said points to each 35 of said indicators, each of said points capable of exhibiting first or second potentials, said number of points connectable to each of said indicators being no greater than said first plurality of translucent portions, said first potential being effective to actuate said indicator lamps, 40 said gate means being controlled by said means for rotating said drums.

9. The unit defined in claim 8 wherein the cross-sectional area of each of said drums is N sided polygonal surface, N being equal to said plurality of rows, and said means for rotating said drums includes a manually operated wheel and a gear train actuated by said wheel coincidently and equally rotating each of said drums.

10. A display system for monitoring the potential at 50 a plurality of points including a display panel having a plurality of apertures formed therethrough, a number of indicators adapted to be actuated by a given potential mounted in a row behind said panel at each of said apertures, a moveably mounted indicia bearing unit associated with said apertures, said unit having N rows 55 of indicia for each of said apertures, each indicium identifying one of said plurality of points, control means for selectively positioning said unit in one of N positions, each of said N positions displaying a different one of said N rows of indicia associated with each of said apertures, a switch circuit applying said given potential on a chosen one of N output lines, said control means selecting a different output line for each of said N unit positions, and gate circuitry connected between said points and said switch circuit and said indicators, said switch circuit output determining which of said points may be effective to actuate said indicators.

11. The system defined in claim 10 wherein said gate circuitry includes an And gate connected to each of said points, the outputs of N of said And gates being connected to each of said indicators, each of said N output lines of said switch circuit being connected to one of said N And gates connected to each of said indicators, said indicia being arranged on said unit so that the indicia visible through said aperture identify the points whose

associated AND gates are enabled by the application of said given potential from said switch circuit.

12. The system defined in claim 10 wherein said unit includes a transparent sheet, mounted between said indicators and said apertures, said indicators emitting radiation when actuated causing a visible display through said apertures, and rack and pinion means for selecting one of said N positions.

13. The system defined in claim 12 wherein said unit includes a number of N sided drums equal to the number of said apertures, each side of each of said drums having indicia thereon, and a gear train manually oper-

able to simultaneously position all of said drums so that one of said N sides is visible at each of said apertures.
